UNITED STATES PATENT OFFICE.

PETER R. WARREN, OF BOSTON, MASSACHUSETTS.

FOLDING BOX.

1,136,454.

Specification of Letters Patent. Patented Apr. 20, 1915.

Application filed December 30, 1914. Serial No. 879,640.

To all whom it may concern:

Be it known that I, PETER R. WARREN, a citizen of the United States, residing at Boston, county of Suffolk, State of Massachusetts, have invented a certain new and useful Improvement in Folding Boxes, of which the following is a specification, reference being had therein to the accompanying drawings.

10 The object of the invention is to provide a paper box which can be used for putting up various articles of merchandise as for instance a candy box and which may also have combined therewith and forming a part of the box a toy attachment representing movable figures, the box being so constructed that these figures may be actuated to go through various motions.

15 The invention will be fully understood from the following description taken in connection with the accompanying drawings and the novel features thereof will be pointed out and clearly defined in the claims at the close of the specification.

20 In the drawings,—Figure 1 is a front elevation of a box embodying the invention. Fig. 2 is a section on line 2—2 of Fig. 1. Fig. 3 is a section on line 3—3 of Fig. 1. Fig. 4 is a view showing the box embodying the invention being manipulated by the hand of the operator. Fig. 5 is a plan of a blank from which the box is formed before it is folded. Fig. 6 shows the box partially folded but in knock down form.

25 Referring to the drawings,—the panel A which is the front or face panel of the box is formed with an upper portion 1 and a lower portion 2 having a thin opening or slit 3 transversely across the face of the panel between the said upper portion 1 and lower portion 2. The lower end panel 4 of the box is hinged to the back panel 5 which is opposite the face panel A, preferably being integral therewith, the hinge being formed by creasing the paper along the folding line between the back panel 5 and the end panel 4. The lower edge of the portion 2 of the face panel A is free thus making the said portion 2 a sort of strap. The two side panels 6, 7 are preferably integral with the face panel A and the said two side panels 6, 7 are preferably respectively formed with flaps 8, 9 which turn in at the lower end of the box inside of the

lower end panel 4 so as to prevent leakage 55 at the ends of the panel 4. The end panel 4 is formed with a divided extension flap forming two portions 10, 11 referred to hereinafter as extension members or figures, side by side and connected with the end panel 4, these two extension members being separated from each other by cutting out a portion of the flap of which they are formed between the said two extension members down to the point where the said extension members both join the panel 4 and they are creased along the joint line between the extension members and the panel. It is to be noted that the lower portions of these extension members 10, 11 have their inner 60 edges 12, 13 respectively formed so as to diverge from each other from the lower end 65 upward for some distance. These extension members when folded along the line at their junction with the panel 4 may be tucked in 70 under the lower portion 2 of the face panel A and pass through the slit 3 and then lap over onto the outer face of the panel portion 1. The portions of these extensions which are visible above the slit 3 are cut out and 75 preferably printed to represent various figures, as for instance individuals or animals or any other form desired. Now by holding the box in one hand and then with the thumb or one of the fingers of the other 80 hand pressing in upon the outer face of the panel 4 in the middle thereof the said panel 4 will be bent inwardly as shown in Fig. 4 and in so doing the figures of the extension members 10, 11 will be caused to diverge 85 from each other; then when said pressure on the lower panel is released the natural resiliency of the paper or cardboard of which the box is formed will cause the said panel to spring back into its normal flat 90 form and the two figures on said extension members will approach each other, coming back into the normal position. The portion 95 2 serves as a strap or guard to retain the extension figures within proper bounds. By 100 manipulation of the said end panel 4 in the manner just described, the two figures represented by said extension members 10, 11 may be made to alternately recede from and approach each other, suggesting dancing if 105 the figures represent individuals, or a boxing match or the antics of animals or the like according to the nature of the figures.

If the panel portion 1 and the face panel A which is overlapped by the extension members 10, 11 have pictures formed thereon these pictures will be more or less exposed 5 and covered again as the extension members are manipulated, thus adding to the apparent number of moving figures. The said extension members may be colored to still further show that they represent the faces and 10 dress and so forth of individuals, animals and the like.

On the lower end of each of the extension members 10, 11 there are formed respectively, 15 the tabs or finger portions 14, 15 which project beyond the end panel and may easily be grasped with the fingers to pull the said extension members partly out, thus giving another set of motions to the figures formed by said extension members. Motion may also 20 be given to said extension members by squeezing in the two opposite side panels 6, 7 at the folding line between the respective ends of the lower portion 2 of the face panel with said side panels which thus bows out 25 the said lower face portion 2 and presses in the two extension members toward each other. In fact it is found by manipulating various portions of the box various motions may be given to the figures represented by 30 said extension members. Such movements may be best given when the box is entirely empty although they may be produced to some extent when the box is partially filled.

In the best embodiment of the invention 35 known to me the entire box and toy attachment is formed out of a single blank died out from a sheet, the flat blank for such purpose being shown in Fig. 5. The face panel A has a transverse slit 3 dividing the panel 40 into the upper and lower sections 1, 2. On opposite sides of the panel A are the two opposite side panels 6, 7 respectively and connected with the side panel 7 is the panel portion 5 which is to form the back panel of the 45 box as already described. Connected with one end of the back panel 5 is the panel 4 which is to form the lower end of the box, and connected with the upper end of the panel A is a panel 16 which is to form the 50 upper end panel of the box. One end of each of the side panels 6, 7 is formed respectively with the flaps 8, 9 which when the box is folded will be turned in and extend part way across the end of the box inside of 55 the end panel 4 and the opposite ends of said side panels 6, 7 are provided respectively with the end flaps 17, 18 respectively which when the box is folded are also turned in to meet each other inside of the end flap 16. 60 The end flap 16 is also formed with a tuck flap 19 which when the box is set up tucks in between the end panel 5 and the edges of the said flaps 17, 18.

The extension members or figures 10, 11 65 are formed integral with the end panel 4 and

as already stated may be formed to represent any kind of an individual, animal, bird, or other creature, but a portion is cut out between the two extension members having diverging edges 12, 13 toward their junction 70 with the panel 4. The panel 4 is also slit to form the finger tabs 14, 15. Connected with the outer side edge of the under panel 5 is a sealing flap 20 which when the box is set up will contact with the inner face of the side 75 panel 2 and is provided with adhesive so that said sealing flap 20 will be sealed to the inner face of the said panel 2. The blank is creased to form folding lines between all of the panels and flaps so that when the sealing flap has been sealed the blank may be knocked down flat in the form shown in Fig. 6 for convenience in packing.

When the box is to be set up the four main panels, that is, the face panel A, the bottom 85 panel 5, and the two side panels 6, 7 will be squared up. Then the two flaps 17, 18 at the upper end of the side panels 6, 7 will be turned in toward each other; the panel 16 will be folded over the outside of the flaps 90 17, 18, and the tuck flap 19 will be tucked in between the inner face of the panel 5 and the edges of the flaps 17, 18. The flaps 8, 9 will also be turned in at right angles to the side flaps 6, 7. The panel 4 will be turned 95 up against the outer faces of the said flaps 8, 9 and the extension members 10, 11 will be tucked in under the lower portion 2 of the face panel A and through the slit 3 and lap over onto the outer face of the portion 1 of 100 the face panel A, leaving the tabs 14, 15 projecting out beyond the end of the box, as shown in Fig. 1. It is immaterial whether the end panel 4 or the end panel 16 is folded first but in filling the box with candy or 105 other merchandise it will be filled after one end is folded and before the other end is folded.

The paper employed for the box blank should be stiff paper or flexible card-board 110 such as is commonly used for making knock-down folding boxes.

While I have described the box as preferably formed of a blank in the manner described, it is obvious that the particular form 11 of blank and of the several panels and method of setting up may be varied, the essential features being the face panel A having two portions 1, 2 separated by a slit 3, an end panel 4 flexibly connected with an 12 under panel 5 and the extension members or figures 10, 11 connected with one panel as the panel 4 and adapted to lie in contact with another panel as the face panel A. It is not even essential that the box should be 13 all integral and it is not essential that the portion 1 should terminate at the upper edge of the lower portion 2.

What I claim is:

1. A box having a plurality of figures 1

cured along one edge thereof to an edge of a panel of the box, and lying in a plane at an angle to the panel to which they are attached, whereby a flexing of the said panel 5 will cause the said figures to be moved relatively to each other.

2. A box having a plurality of figures secured along one edge thereof to an edge of a panel of the box and overlying another 10 panel of the box at an angle to said first mentioned panel whereby a flexing of said first mentioned panel will cause said figures to be moved relatively to each other.

3. A box having a plurality of figures secured along one edge thereof to an edge of a panel of the box and overlying another 15 panel of the box at an angle to said first mentioned panel whereby a flexing of said first mentioned panel will cause said figures to be moved relatively to each other, and a 20 strap parallel to the plane of said second mentioned panel between which and said second mentioned panel said movable figures lie.

25 4. A combination box and toy having a face panel formed with an upper and a lower portion having a transverse slit between them, a back panel opposite the said face panel, an end panel flexibly connected 30 with said back panel, an extension member flexibly connected with the edge of said end panel on the opposite edge from the connection of said end panel with the said back panel, said extension member being tucked in beneath the lower portion of said 35 face panel, and through said transverse slit and lapping over onto the outer face of the upper portion of said face panel, said extension member being divided to form a plurality of figures.

40 5. A combination box and toy having a face panel formed with an upper and a lower portion having a transverse slit between them, a back panel opposite the said 45 face panel, an end panel flexibly connected with said back panel, an extension member flexibly connected with the edge of said end panel on the opposite edge from the connection of said end panel with the said back 50 panel, said extension member being tucked in beneath the lower portion of said face panel, and through said transverse slit and lapping over onto the outer face of the upper portion of said face panel, said extension member being divided to form a plurality of figures, the dividing line between 55 said extension figures extending substantially to the junction thereof with said end flap and having upwardly diverging edges.

30 6. A combination box and toy having a face panel formed with an upper and a lower portion having a transverse slit between them, a back panel opposite the said 35 face panel, an end panel flexibly connected 40 with said back panel, an extension member

flexibly connected with the edge of said end panel on the opposite edge from the connection of said end panel with the said back panel, said extension member being tucked in beneath the lower portion of said face 70 panel and through said transverse slit and lapping over onto the outer face of the upper portion of said face panel, said extension member being divided to form a plurality of figures, the dividing line between 75 said extension figures extending substantially to the junction thereof with said end flap and having upwardly diverging edges and finger tabs connected with said extension members and projecting beyond the 80 end of the box.

7. A combination box and toy formed of a single blank cut from a sheet of paper having flap and panel portions to form a six sided folding box with tuck flaps for 85 the ends and a side sealing lap, said blank being creased along the dividing lines between the several panel and flap portions, the face panel having a strap portion intermediate its upper and lower ends, the lower 90 end panel having a plurality of extension members beside each other which when the box is folded are tucked up underneath the said strap portion of said face panel and onto the outer face of the upper portion of 95 said face panel.

8. A combination box and toy having a face panel formed with a strap portion intermediate its upper and lower ends, a back panel opposite the said face panel, an end 100 panel flexibly connected with said back panel, an extension member flexibly connected with the edge of said end panel on the opposite edge from the connection of said end panel with the said back panel, 105 said extension member being tucked in beneath the said strap portion and lapping over onto the outer face of the upper portion of said face panel, said extension member being divided to form a plurality of 110 figures which are shaped and colored to represent living creatures.

9. A combination box and toy having a face panel formed with a strap portion intermediate its upper and lower ends, a back 115 panel opposite the said face panel, an end panel flexibly connected with said back panel, an extension member flexibly connected with the edge of said end panel on the opposite edge from the connection of 120 said end panel with the said back panel, said extension member being tucked in beneath the strap portion of said face panel and lapping over onto the outer face of the upper portion of said face panel, said extension member being divided to form a plurality of figures, the said end panel with which the extension members are connected being flexible and resilient.

10. A combination box and toy having a 125

4

face panel, a back panel, an end panel flexibly connected with the back panel and having an extension portion connected with the edge of the end panel opposite the edge which is connected with the back panel, said extension member being divided to form a plurality of figures which lap over onto the face of the face panel and a strap portion which overlies the lower part of

said extension members in a manner to permit sliding movement of said extension members under said strap portion. ¹⁰

In testimony whereof I affix my signature, in presence of two witnesses.
